The ornamental design for a male keyed lamp plug, as shown and described.

DESCRIPTION

FIG. 1 is a perspective view of a male keyed lamp plug according to the invention.

FIG. 2 is a top view of the male keyed lamp plug of FIG. 1.

FIG. 3 is a front view of the male keyed lamp plug of FIG. 1.

FIG. 4 is a bottom view of the male keyed lamp plug of FIG. 1.

FIG. 5 is a left side view of the male keyed lamp plug of FIG. 1. The right side view is identical to the left side view; and,

FIG. 6 is a rear view of the male keyed lamp plug of FIG. 1.

The broken line portion of the figure drawings is included to show unclaimed subject matter only and forms no part of the claimed design. The undulating break lines shown at the rear of the article indicate a symbolic break in its length, the appearance of any portion of the article beyond the break line forms no part of the claimed design.

This design is directed to a male keyed lamp plug for electrical devices.
